UNITED STATES PATENT OFFICE

153,665

DESIGN FOR A FLUORESCENT LIGHTING FIXTURE

Carl C. Braun, Riverside, Conn.

Application March 29, 1948, Serial No. 145,411

Term of patent 7 years

(Cl. D48—23)

To all whom it may concern:

Be it known that I, Carl C. Braun, a citizen of the United States of America, residing at Riverside, in the county of Fairfield and State of Connecticut, have invented a new, original, and ornamental Design for a Fluorescent Lighting Fixture, of which the following is a specification, reference being had to the accompanying drawing, forming part thereof.

In the drawing

Fig. 1 is a perspective view of a fluorescent lighting fixture, showing my new design,

Fig. 2 is a front elevational view thereof, and

Fig. 3 is an end elevational view.

The broken lines shown in the drawing are for illustrative purposes only.

I claim:

The ornamental design for a fluorescent lighting fixture, as shown and described.

CARL C. BRAUN.
